UNITED STATES PATENT OFFICE.

H. CLAY BASCOM AND CYRUS A. HODGES, OF TROY, NEW YORK, ASSIGNEES
TO SAID BASCOM.

DESIGN FOR A COOKING-STOVE.

SPECIFICATION forming part of Design No. 15,399, dated September 16, 1884.

Application filed June 17, 1884. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Cooking-Stoves, of which the following is a specification, reference being had to the accompanying cut, print, or engraving of a cooking-stove having our said new design.

This design embraces several new and distinct parts and combinations of parts which go to make up with beneficial effect the whole 15 design, as shown in the accompanying illustration, and hereinafter described.

One part is the shape and ornamentation of the front door, A, consisting of the upper portion, B, having the angular border *a*, the ornamented curved surface *b*, and the three quadrilateral mica lights *c*, with truncate corners, the inclined part *d*, and the flat lower portion, C, having the six draft-apertures *e*, with truncate upper corners, and the intermediate ornaments, *f*.

The general trapezoidal shape of the door or panel D is not new; but the same when ornamented by the corner ornaments, *i*, and central ornament, *i'*, is a part of this design.

The general shape of the oven-door E having the border *j* is not new; but the ornamentation of that door by the corner ornaments, *l*, and the central ornament, F, consisting of the parts *m n o n'* is a distinctive part of this design.

The ornamentation of the rear side panel, G, having the rectangular border *p*, consists of the corner ornaments, *r*, and central ornament, *r'*, on the curved rectangular surface *q*.

The ornamentation of the rear bracket-plate, H, having the border *s*, of curved and angular shape, consists of the compound corner ornament, *t*.

The design for the legs I consists of the top

ornamental band, *u*, the convex upper portion, 45 *r*, having the ornament *w*, the curved and contracted lower portion, *y*, and the bead-edging *x*.

The whole design embraces the shape and ornamentation of the top, the front, including 50 the door A, hearth-plate, and forward extension, the side, including the portions D, E, G, and H, and the legs.

We claim as new—

1. In a design for a stove, the shape and ornamentation of the front door, A, consisting 55 of the parts B, *d*, and C, as shown and described.

2. In a design for a stove, the shape and ornamentation of the door or panel D, consisting 60 of the parts *g h i i'*, as shown and described.

3. In a design for a stove, the ornamentation 65 of the oven-door E, consisting of the parts F and *l* on the surface, surrounded by the border *j*, as shown and described.

4. In a design for a stove, the ornamentation 70 of the rear side rectangular panel, G, consisting of the parts *r* and *r'* on the surface *q*, surrounded by the border *p*, as shown and described.

5. In a design for a stove, the shape and ornamentation of the bracket-plate H, consisting 75 of the parts *s* and *t*, as shown and described.

6. In a design for a stove, the shape and ornamentation of the legs, consisting of the parts 80 *u v w x y*, as set forth.

7. The design for a cooking-stove, consisting 85 of the top, front, side, and legs, shaped and ornamented as described and shown.

In testimony whereof we hereunto set our hands, in the presence of two subscribing witnesses, this 14th day of June, 1884.

H. CLAY BASCOM.
CYRUS A. HODGES.

Witnesses:

CHARLES H. BENEDICT,
CHESTER BASCOM.
